UNITED STATES PATENT OFFICE.

EDWARD J. OVINGTON, OF LOS ANGELES, CALIFORNIA, ASSIGNOR, BY MESNE ASSIGNMENTS, TO SIMPLEX ELECTRIC HEATING COMPANY, OF CAMBRIDGE, MASSACHUSETTS, A CORPORATION OF MASSACHUSETTS.

IMMERSION-HEATER.

1,117,950.

Specification of Letters Patent.

Patented Nov. 17, 1914.

Application filed December 1, 1911. Serial No. 663,818.

To all whom it may concern:

Be it known that I, EDWARD J. OVINGTON, a citizen of the United States, residing at Los Angeles, in the county of Los Angeles 5 and State of California, have invented new and useful Improvements in Immersion-Heaters, of which the following is a specification.

This invention relates to immersion heaters, and more particularly to such heaters the heat units of which are electrically generated or supplied, heaters so organized being particularly adapted for immersion 10 in water and other fluids for raising the 15 temperature thereof.

This invention in its general aspects constitutes a departure from or improvement with relation to the subject-matter covered by prior Letters Patent No. 994,188 issued 20 to me June 6, 1911, for an electric heating unit; and the leading and more significant features of improvement entering into the present invention pertain to the broad class 25 of heating units as well as specifically to immersion heaters having means for electrically supplying heat units.

According to the present invention, I provide an insulating body within which the electrical resistance element is disposed, such insulating body being in the main surrounded by a metallic closely-fitting shell, a stem projecting from the upper portion of the body, and a metallic cap fitting the lower portion of the body and joined or sealed to the shell, preferably by a solder joint. In order to render the joint completely liquid-proof, and in fact to inclose the entire insulating body and shell and cap in a liquid-proof sheath, I impose upon 30 the shell and the cap, and the joint between the shell and cap, a copper or other metallic plating. The flexibility of the copper plate compensates responsively for any expansion or contraction of the metallic shell 35 and cap and the solder joint, if there be such, between the same, as under widely varying temperatures causing melting of the solder; and if the joint tends to yawn or open, as after melting of the solder, it is 40 effectually maintained liquid-proof by the copper plating over the same. This plating, due to its flexibility and ductility, compensates as above stated for any disturbance 45

of the joint and for any contraction and expansion incident thereto. All danger of 55 short-circuiting or ground of the resistance element due to liquid conduction is therefore eliminated.

A principal feature and advantage of the invention will therefore be seen to consist in the provision of a heating unit 60 inclosed first in a two-part metallic inner casing, and second in a single continuous outer metallic sheath positively preventing passage of liquid to the heating unit 65 through the joint between the two parts of the inner casing, such sheath being capable of expansion and contraction and of material stretching at such joint. Furthermore, I provide a superficial conformation 70 of the entire body organized as above, which is predicated upon a transverse section of varying dimensions, as of oval or elliptical formation. The body may also be of increasing cross-sectional area, as from the 75 top to the bottom thereof, preserving still the stated formation of such area. The conformation described provides for a relatively large surface in proportion to displacement, directly presented to the liquid 80 within the smallest vessel within which the heater may be introduced, and consequently for a relatively great transmission of heat units to the liquid.

In addition to the above advantages, the 85 conformation stated is, because of its unbroken and regular surface, more readily kept clean than are other forms such as fluted, wavy or the like.

With the above and other objects in view, 90 and the above and equivalent means and features entering into the embodiment thereof, the invention consists in the novel and useful provision, construction, formation, combination, association and relative arrangement of parts, members and features, 95 as hereinafter described, shown in the drawing, and finally pointed out in claims.

In the drawing: Figure 1 is a side elevation of an immersion heater or heating unit 100 organized in accordance with the invention; Fig. 2 is a transverse sectional view, taken upon the line 2—2, Figs. 3 and 4; Fig. 3 is a view similar to Fig. 1 of a modified form of construction; Fig. 4 is a central 105 vertical sectional view taken through the

showing in Fig. 1; and Fig. 3 is a fragmentary view similar to Fig. 4, of a still further modified form of construction.

Corresponding parts in all the figures are denoted by the same reference characters.

Referring with particularity to the drawing, A in Figs. 1, 2, 4 and 5, and B in Figs. 2 and 3, designate an electrical heating unit or immersion heater, the construction and organization of both forms, A and B, being the same, with the exception of exterior conformation. This conformation is shown in the form A as being elliptical or oval in cross-section, each cross-section being constant throughout the major portion of the heater. In the form B, the cross-sectional area is elliptical or oval, the same as in the form A, as shown in Fig. 2, but, as shown in Fig. 3, the said cross-sectional area varies in different transverse planes of the heater, the dimensions of such cross-sectional area preferably increasing downwardly through the major portion of the heater, whereby the heater has a resultant conformation which may be termed a tapered, flattened or contracted truncated cone.

Each of the heaters A and B is provided with an upwardly extending stem C through which electrical conductors are led to the heater through any suitable insulation. Apart from the geometrical formation or superficial area of the heaters, the construction and organization of both forms A and B being the same, I will only refer to the latter with respect to the form shown in Figs. 1, 2, 4 and 5, and the organization therein is as follows:—The heater has a body a of insulating material within which is arranged or disposed a resistance element b of any preferred nature, the particular qualities and characteristics of the insulating element and the resistance element being not concerned in the present invention. The resistance element is electrically connected with conductors c and d, within the stem C, for supplying electrical energy. Surrounding the body a or the major portion thereof, at the sides and top part way upwardly therefrom upon the stem C, is a shell e formed or spun upon the body a and closely fitting the same. Formed upon and covering the lower end of the body a is a cap f, the lower marginal portions of the shell e overlapping over the marginal portions of the cap f, and a joint g being formed between such overlapping portions in Fig. 4, a modified form of joint m being shown in Fig. 5, the former consisting preferably of a mass of solder or the equivalent applied between the overlapping shell and cap. The extreme lower edge portion of the shell is closely engaged with the solder of the joint, being preferably spun, pressed or beaten down upon the same to form a thin feather edge h between the extremity of which and the cen-

tral portion of the cap the solder extends, as well as extending between the directly overlapping portions of the cap and shell. The extreme marginal portions of the cap extend preferably into contact with the inner walls of the shell at the sides of and beneath the body a. Over the said shell e and cap f and the joint g between the same, I spread a copper plating k which might extend above the body part way upwardly of the stem C.

In Fig. 5 I have shown the joint m as consisting of the over-lapped marginal portions of the shell and cap with the extreme marginal portions of the shell spun, pressed or beaten down upon the cap to form the thin beaten edge h, no solder being interposed between the shell and the cap. The extreme marginal portion of the cap is received in an annular groove formed in the shell e at the bend in the same where the overlap of the shell upon the cap commences. The metallic plating is then produced upon and over the shell and cap and joint m, and serves to maintain the joint liquid-proof, accommodating by its flexibility and ductility any expansion and contraction at the joint.

As initially pointed out, and made manifest by the foregoing description taken in connection with the accompanying drawing, it will be noted that the copper plating effectually liquid-seals the entire heater, or the working portion thereof which is immersed, preventing leakage through any part of the shell e or the cap f or the joint g between the same; and that any shrinkage or enlargement of the joint will be accommodated by the flexible and ductile copper plating. Furthermore, an effective joint g or m is formed by thinning down the material of the shell into an extremely fine edge which overlies the solder between the overlapping portions of the shell and cap, or, as in Fig. 5, directly overlies the cap. The superficial conformation of the heater provides for dissemination of a large number of heat units through a relatively large volume of liquid within the smallest container which will receive the heater. This effect may be varied or slightly enhanced by the provision of the conformation and cross-sectional area disclosed in Figs. 2 and 3, relative to the form B, which is oval or elliptical in cross-sectional area, but exteriorly of tapered and contracted conical conformation.

The heat generated by the electrical resistance passes from the resistance element b, the resistance being served by the conductors c and d, as will be readily understood; the heat units so generated being transmitted to the liquid surrounding the working heater from and by the copper plated exterior surface of the heater.

I do not desire to be understood as limit-

ing myself to the specific provision, construction, formation, combination, association and relative arrangement of parts, members and features shown and described; 5 but reserve the right to vary the same, in adapting the improvements to varying conditions of use, without departing from the spirit of the invention and the terms of the following claims.

10 Having thus described my invention, I claim and desire to secure by Letters Patent:—

1. An electrical heating unit of the character set forth, comprising an insulating body provided with a resistance element, a shell and a cap upon and surrounding the body, and a water tight connection of the cap and shell comprising a solder joint be-

tween the shell and cap, and a copper plating over the joint.

2. An electrical heating unit of the character set forth, comprising an insulating body provided with a resistance element, a shell and a cap surrounding the body, there being a solder joint between the shell and the cap, and a marginal portion of the shell being relatively thin-edged at the solder joint overlapping said cap and a copper plating over the joint.

30 In testimony whereof, I have signed my name to this specification in the presence of two subscribing witnesses.

EDWARD J. OVINGTON.
